UNITED STATES PATENT OFFICE.

EUGENE PETERSON, OF NEW YORK, N. Y., ASSIGNOR, BY MESNE ASSIGNMENTS, TO
WESTERN ELECTRIC COMPANY, INCORPORATED, A CORPORATION OF NEW YORK.

MODULATING SYSTEM.

Application filed April 15, 1925. Serial No. 23,232.

To all whom it may concern:

Be it known that I, EUGENE PETERSON, a citizen of the United States of America, residing at New York, in the county of New York, State of New York, have invented certain new and useful Improvements in Modulating Systems, of which the following is a full, clear, concise, and exact description.

10 This invention relates to modulating systems and more particularly to tandem arrangements of modulating devices.

An object of the invention is to increase the modulated output of a space discharge 15 modulating and amplifying system.

It is well known that space discharge amplifiers function simultaneously as amplifiers and as modulators, due to the non-linear relation that exists between the impressed E. M. F. and the space current. If the impressed E. M. F. is a single pure sinusoidal wave the modulation products appear in the output as harmonics together with a steady D. C. component, and if the impressed wave comprises two or more sinusoidal components the modulation products will comprise a large number of components including those whose frequencies are the sum and the difference of the impressed wave frequencies.

In high frequency transmission systems, it is a common practice to modulate a carrier wave in accordance with a low frequency signal and subsequently to amplify 35 the modulated carrier wave in one or more stages of amplification prior to transmission.

In accordance with this invention, the subsequent stages of amplification are caused 40 to contribute additional modulation products of the useful frequencies and in the proper phases so that the final modulated output is increased.

An object of the invention is therefore to 45 provide a modulating and amplifying system in which the functions of modulation and amplification are usefully combined in a single device.

The nature of the invention and its mode 50 of operation is more fully disclosed in the detailed description which follows read in conjunction with the accompanying drawing of which Figs. 1 and 2 represent in schematic form two systems embodying the invention in alternative forms.

The system of Fig. 1 is arranged to deliver a speech modulated carrier frequency current to a load impedance 6, which may in practice be a wire transmission line, or a radiating antenna system, or other type of load by which the energy is usefully absorbed. The carrier frequency wave is supplied by a high frequency generator 8 from which it passes through high-frequency transformer 9 to the input of space discharge device 1 and subsequently through similar space discharge devices 2 and 3. The space discharge devices 1, 2 and 3 are amplifying vacuum tubes of the well known three-electrode type. They are coupled in tandem by means of high frequency transformers 4 and 5 and the last tube 3 is connected to the load by high frequency transformer 7.

The speech waves by which the carrier wave is modulated are generated in microphone 10 and are transmitted through transformer 11 to the primary windings of the three low-frequency transformers 12, the secondary windings of which are connected in the input circuits of the successive amplifier tubes 1, 2 and 3. Low pass filters 13 of similar construction are connected between each of the transformers 12 and the source of speech waves to prevent the feeding back of carrier frequency energy through the speech input circuits. These filters may be of the well known Campbell type as disclosed in U. S. Patent 1,227,113 issued May 22, 1917, but if the carrier wave frequency is very high, as it would be in some radio systems, it will in many instances be sufficient to use, instead of the filters, simple condensers connected in shunt across the primaries of transformers 12, or a single condenser across the secondary winding of transformer 11.

Space current is supplied to the discharge tubes from direct current sources 15 and the control electrodes are polarized by batteries 14. The voltages of the polarizing batteries should be such that the discharge tubes operate under substantially similar conditions. It is preferable that the control electrodes be polarized negatively under which condition a positive increment of the control electrode potential will produce an increase in the space current greater than the decrease produced by an equal negative increment. In other words the preferred con-

dition of operation is that under which the space current increases more rapidly than the control electrode potential. If the discharge tubes are all alike the potentials of batteries 14 should be equal but if tubes of increasing power capacity are used in the successive stages the potentials applied to the control electrodes will in general require to be proportioned differently to produce 10 the required condition of operation in each type of tube.

Non-reactive resistances 16 connected in shunt to the secondary windings of high frequency transformers 9, 4 and 5 serve to 15 make the system substantially non-reactive to high frequency waves, and so to prevent undesirable changes in phase of these waves as they are repeated by the successive discharge tubes.

20 The manner in which the system operates and the precautions that must be taken to secure the desired object will now be described.

With respect to the carrier frequency 25 wave the system operates simply as a multi-stage amplifier, the wave from source 8 being repeated with successively amplified energy by the discharge tubes 1, 2 and 3 and finally delivered to the load 6.

30 The speech waves impressed upon the control electrodes of each tube cause corresponding speech frequency currents to flow in the space paths, and these, interacting with the amplified carrier frequency currents, generate 35 additional waves or modulation products, the important products being those of the summation and of the difference frequencies, or, as they are commonly called, side band waves.

40 Transformers 4 and 5 being designed to operate efficiently at carrier frequencies are very inefficient at speech frequencies and consequently little or no speech frequency E. M. F. is transmitted from the output of 45 one tube to the input of the succeeding tube. The side band waves, however, being also of carrier frequency, are efficiently transmitted.

50 In each tube therefore there are generated separate side band waves, and further in tubes 2 and 3 the side band waves generated in or repeated by the previous tubes are also present.

55 The successful operation of the system depends upon these various side band waves being substantially in phase in the output circuit of each tube so that they reinforce each other. By similarly poling the windings of transformers 4, 5 and 9 the phase 60 of the carrier wave impressed on each tube may be made the same. It follows therefore that the side band products of tube 1 will, in the output circuit of tubes 2 and 3, be in the same phase as in the output of the 65 first tube.

By poling alike the windings of transformers 12 also, the separately generated side bands will be of like phase in the output circuits of all tubes, and, since they are repeated by the successive tubes without 70 change of phase, the desired result of their mutual reinforcement is obtained.

The system of Fig. 2 differs from that of Fig. 1 in that the carrier and speech wave sources are connected to the first tube only 75 and are impressed upon the succeeding tube by being repeated through a coupling circuit designed to transmit efficiently waves of both high and low frequencies. The input circuit of space discharge tube 19 is connected to a microphone circuit by transformer 17 and to the source 8 of carrier waves by transformer 18. The succeeding discharge tube 20 is connected to the output terminals of tube 19 by a coupling circuit comprising a high inductance choke coil 22 through which the space current for tube 19 is supplied, a series condenser 23 of high capacity, and a high resistance 24 connected in shunt to the input terminals of tube 20. The modulated wave output of tube 20 is delivered to the load impedance 6 through high frequency transformer 25.

80 The operation of this system is similar to that of the system already described. 85 With the direct coupled arrangement of the tubes the phase of the carrier wave is the same at the input terminals of each tube as also is the phase of the speech wave. The 90 separately generated side bands are therefore in like phase in the output circuit of each tube and consequently the side bands repeated by the second tube are in phase with those separately generated therein. The 95 mutual reinforcement of the side band components is therefore obtained by this system also.

100 What is claimed is:

1. A modulating system comprising a plurality of space discharge amplifiers having 110 anodes, cathodes, and control electrodes, coupling circuits for connecting said amplifiers in tandem whereby waves repeated in the space path of one amplifier are impressed upon the control electrode of the succeeding 115 amplifier, a source of carrier waves, a source of signal waves, means for impressing simultaneously upon the control electrode of said amplifiers waves derived from both of said sources whereby the carrier wave is separately modulated in each amplifier, and means for controlling the phases of the waves in the space path of each amplifier so that the modulation products separately produced reinforce the modulation products, repeated from the preceding amplifiers. 120

2. A modulation system comprising a plurality of space discharge amplifiers having 125 anodes, cathodes and control electrodes, a source of carrier waves, and a source of sig- 130

nal waves, said amplifiers being connected in tandem to the source of carrier waves, and the control electrodes of each of said amplifiers being coupled separately to said source 5 of signal waves.

3. A modulation system comprising a plurality of space discharge amplifiers having anodes, cathodes, and control electrodes, a source of carrier waves, said amplifiers being connected in tandem to said carrier wave source, a source of signal waves, and coupling means for impressing said signal waves upon the control electrode of each amplifier separately, said coupling means being 10 adapted to control the phases of the impressed signal waves whereby the modulation products separately produced in each amplifier are caused to reinforce similar products repeated from the preceding amplifiers.

4. A modulation system comprising a plurality of space discharge amplifiers having anodes, cathodes and control electrodes, a source of carrier waves, said amplifiers being connected in tandem to said source by coupling circuits selective to carrier frequencies, a source of low frequency waves individual coupling circuits for impressing said low frequency waves upon the control electrode of each amplifier, and means included in said coupling circuits to prevent the transfer of carrier frequency waves therethrough, said coupling circuits being adapted to control the phases of the impressed low frequency waves whereby the modulation products separately produced in each amplifier are caused to reinforce similar products repeated from the preceding amplifiers.

40 5. A modulation system comprising a plurality of space discharge amplifiers in tandem having anodes, cathodes and control

electrodes, the control electrodes of said amplifiers having normal potentials of such magnitudes that the space currents in each 45 amplifier have similar variations with respect to the control electrode potentials, input circuits and output circuits connected respectively between the control electrodes and the anodes to the cathodes of said amplifiers, a source of low frequency waves, a source of high frequency waves, transformers selective to high frequencies connected in said input and said output circuits whereby the amplifiers are connected in tandem to 50 said high frequency source, and transformers 55 selective to low frequencies connected in said input and said output circuits whereby the secondary windings connected in said input circuits and their primary windings connected in common to said low frequency 60 source, the windings of said high frequency transformers being similarly poled and the windings of said low frequency transformers being also similarly poled whereby the modulation products generated in each amplifier are caused to reinforce similar products 65 repeated from the preceding amplifier.

6. A modulation system comprising a plurality of space discharge amplifiers each having an anode, a cathode, and a control 70 electrode, a circuit including said amplifiers connected in tandem, a source of carrier waves, a source of signal waves, means for supplying waves from said sources to said amplifier circuit to produce modulation 75 products in each amplifier and means for controlling said amplifiers so that the modulation products produced by each amplifier reinforce the modulation products repeated 80 thereby.

In witness whereof, I hereunto subscribe my name this 10th day of April, A. D. 1925.

EUGENE PETERSON.
